UNITED STATES PATENT OFFICE

134,952

DESIGN FOR A LACE

Abraham Feerst, New York, N. Y.

Application January 12, 1943, Serial No. 109,237

Term of patent 3½ years

To all whom it may concern:

Be it known that I, Abraham Feerst, a citizen of the United States, residing in New York city, in the county of Bronx and State of New York, have invented a new, original, and ornamental Design for a Lace, of which the following is a specification, reference being had to the accompanying drawing, forming part thereof.

The figure of the drawing is a plan view of a

piece of lace showing my new design on a dark background, so as to bring out more clearly the details thereof, a unit of which is contained by the dot and dash lines.

I claim:

The ornamental design for a lace, substantially as shown and described.

ABRAHAM FEERST.
